U. S. Pat. Off. Feb 12, 1836

John Philbrick Wilkinson, Mississippi

Letter Patent

The Schedule is found to be these Letters Patent and making part of the same containing a description in the words of the said John Philbrick himself of his improvement in the Apparatus for Drying Cotton and other articles.

To all whom it may concern. Be it known that I John Philbrick of the County of Wilkinson in the State of Mississippi have invented an apparatus for the drying of Cotton after it has been picked from the plant and of a great variety of vegetables and other substances which are quite exposed to the sun and air and by which of course they may be immediately protected from the effects of rain and violence, and I do hereby declare that the following is a full and exact description thereof referring back to the drawing which accompanies and makes a part of this Specification.

There a stage consisting of parallel said which are supported platforms being a car upon which the cotton or other articles to be dried are to be spread. These cars or platforms may be of any convenient dimensions but for the sake of description we will suppose them to be made square side with eight feet long and three feet open which they are to be dry houses in height. On the accompanying drawing one of these cars is marked by the letter C and about six inches to the height of the platform above the rail upon which it rides at its left end. P. B. R. L. are platforms brought a car which rest and run upon the rail having wheels or rollers upon them made for that purpose.

The rail upon which the platforms rest ride one above the other in the form of steps as done in the drawing. The platform marked C is represented as having passed from the right hand rail on to the next platform having been pushed forward by the man A and now stands upon the platform on the next rail against which it is butting and both press together and the man in the center is pushing them as already shown.

There at the top hand of the rail each side in, in the same way when necessary and lay over the other on a catch or catch by which the two platforms are held together a released a platform can

72. 9392x

useable steps for conveniently reaching, cleaning and discharging the platform.
Although the only of such platforms are represented as extending on each side of the
stack the number to be used is limited only by the convenience with which they
may be managed and this is the case also with their dimensions.

The mode of managing these also will admit of
being varied whilst the principles upon which they operate will remain unchanged.
Thus for example the shed may be made to cover the highest platform and be left
perpendicular so as to gather all the rain on platforms under it in its progress the platform
may be in a single row or there may be two or three rows the width being shown
in the drawing. The platform may be run under the shed by hand or by means of a
winch with a windlass and rope or otherwise. Having thus fully explained the
general construction and use of my said apparatus I wish it to be distinctly re-
marked that I do not intend by the example given to limit myself thereby but
I say the same in any way I may think proper, whilst the proposed end is attained
by analogous means. What I claim as my invention is the construction of a sail
say in ship's pin slips and having upon them two platforms upon which article
to be cleaned may be exposed to the sun and air and which may in a few seconds
be poised upon each other under a shed to protect them from the weather when
recapting to the manner upon the principles herein set forth.
